**REFERENCE ELECTRODE HOUSING FOR A
MARINE CATHODIC PROTECTION DEVICE**

Edward P. Anderson, Fond du Lac, Wis., assignor to
Brunswick Corporation, Skokie, Ill.

Filed Mar. 29, 1973, Ser. No. 345,870

Term of patent 14 years

Int. Cl. D12—99

U.S. Cl. D12—155

FIG. 1 is a perspective view of the reference electrode housing for a marine cathodic protection device of my design;

FIG. 2 is a front view of the reference electrode of FIG. 1;

FIG. 3 is a left side view of the reference electrode of FIG. 1;

FIG. 4 is a bottom view of the reference electrode of FIG. 1; and

FIG. 5 is a rear view of the reference electrode of FIG. 1.

The left and right side views of the reference electrode of FIG. 1 are identical.

I claim:

The ornamental design for a reference electrode housing for a marine cathodic protection device, substantially as shown and described.
